UNITED STATES PATENT OFFICE.

LEWIS L. TATUM, OF NORWOOD, OHIO, ASSIGNOR TO THE CUTLER-HAMMER MFG. CO., OF MILWAUKEE, WISCONSIN, A CORPORATION OF WISCONSIN.

MULTIPLE-SWITCH STARTER.

No. 918,608.

Specification of Letters Patent. Patented April 20, 1909.

Application filed May 20, 1907. Serial No. 374,705.

To all whom it may concern:

Be it known that I, LEWIS L. TATUM, a citizen of the United States, residing at Norwood, in the county of Hamilton and State 5 of Ohio, have invented new and useful Improvements in Multiple-Switch Starters, of which the following is a full, clear, concise, and exact description, reference being had to the accompanying drawing, forming a part 10 of this specification.

My invention relates to improvements in motor controllers. It is particularly applicable to controllers in which a plurality of hand operated switches are used for controlling a resistance.

According to the preferred form of my invention, I provide a plurality of hand operated switches which are adapted to be closed in a definite sequence to remove the starting 20 resistance from the motor circuit, and one of which controls the motor circuit. These switches are maintained in their closed position, preferably by a low voltage device. This device is adapted to cause the switches 25 controlling the motor circuit to open the circuit upon failure of voltage or in event the voltage falls below a predetermined point. The resistance of motor starting devices is usually formed of wire which while it is of 30 sufficient capacity to carry the current for a short time, during the starting of the motor, is not of sufficient capacity to carry the current for a considerable period. It is therefore desirable to make some provision where- 35 by in event a careless or ignorant operator leaves the starting resistance in circuit for longer than a predetermined period the circuit will be opened. In the present invention I accomplish this by providing a switch- 40 ing device which has a tendency to move to operative position and which when in operative position either opens the circuit through said low voltage device or closes a short circuit around the same. This switching de- 45 vice is set or moved to inoperative position by each switch as it is closed and then released to permit it to move to operative position. Before, however, it reaches operative position the next switch is closed. If 50 the next switch is not closed then the low voltage device releases the switches closed and opens the circuit. The last switch of the series is provided with a switch which, when the last switch of the series is closed, is op- 55 erated to render the switching device inef-

fective to cause the low voltage device to release the switches. By this means the operator must close each switch within a predetermined time after its preceding switch or all the switches closed will open and open the 60 circuit.

It is obvious that various changes may be made in my device without departing from the spirit of my invention.

I have illustrated, for the purpose of disclosing my invention, one form of the same in the accompanying drawings.

In said drawings: Figure 1 is a front elevation of a motor starting device embodying my invention, Fig. 2 is an end elevation of my 70 device, a part of the dash-pot being shown in section, Fig. 3 is a similar view with the switches in an open position, Fig. 4 is a sectional view on the line 4—4 of Fig. 1, Fig. 5 is a similar view with the switches open, Fig. 6 75 is a detailed section upon the line 6—6 of Fig. 1, Fig. 7 is a detailed view of the latch mechanism for holding the switches in a closed position, Fig. 8 is a sectional top view of one of the switches and a top view of the 80 coöperating rocking dogs, Fig. 9 is a detailed view of one of the rocking dogs, Fig. 10 is a detail of one of the dogs carried by the operating levers, and Fig. 11 is a diagrammatic view of the circuit connections of my invention. 85

In the embodiment of the invention illustrated, I provide a plurality of switch levers or arms 1, 1^a, 1^b, 1^c, 1^d, 1^e, 1^f, and 1^g, which are suitably pivoted or journaled at one end 90 and are provided at the opposite end with suitable operating handles. I have shown the several switch levers as journaled upon a shaft or rod 2, mounted in bearings 3, formed in suitable brackets 4. The brackets 4 also 95 support a rod 5 which is threaded through a rubber tube 6, which serves as a cushion or buffer against which the extended ends of the switch arms or levers are adapted to impinge when thrown open. Each of the levers 100 carries a contact device 7 made preferably from a number of strips of copper laid face to face, the free ends of which are adapted to engage contact surfaces to complete the electric circuit. Upon the base board 8, 105 upon which the various parts of the device are mounted is mounted a contact bar 9 with which one end of the contact device 7 of each switch is adapted to engage, the other end of said device being adapted to engage one of the 110

contact terminals 10, 10^a, 10^b, 10^c, 10^d, 10^e, 10^f, and 10^g. The contact device of the first and last switch arms is preferably made wider than the remaining contacts, as these contact devices are adapted to carry a larger current than the remaining devices.

Upon the terminal 10 is provided a binding post 11, by which suitable electrical connections are made therewith, and a second binding post 12 is carried by the terminal 10^g. Also upon the terminal 10, and upon the contact bar are mounted a pair of carbon blocks 13 and 14. The first switch arm carries a pair of laterally extending spring arms 15 and 16, upon the ends of which are mounted a pair of carbon blocks 17 and 18 respectively. When the switch arm 1 is moved to close the circuit, the block 17 engages the block 13 and the block 18 engages the block 14, thereby closing the circuit from the terminal 10 to the contact bar 9. The further movement of the switch arm causes the contact device 7 thereof to directly connect the terminals 10 and 9. Likewise when the switch arm 1 is moved outward, the contact device 7 thereof leaves the terminals 10 and 9 before the carbon blocks separate, so that any arc that may be formed by the opening of the circuit will take place between the carbon blocks instead of between metallic surfaces.

Near the upper end of the switch arm 1 is a lug 19, which carries a laterally extending projection 20, which may take the form of a screw. Mounted upon the base board 8 above the arm 1 is a retaining magnet 21, having an armature 22 pivoted at 23. The armature carries a laterally and upwardly extending lug 24, and when the arm 1 is moved to close the circuit, the projection 20 engages the side of the armature 22 to move the same against the magnet pole, and the magnetism of the magnet retains the armature 22 in this position. The swinging of the armature 22 carries the lug 24 upon the exterior of the projection 20 so that the projection will rest in the slot formed between the lug 24 and the armature 22, and as long as the magnet remains energized, the arm 1 will thus be held in the closed position. When, however, the magnet is deenergized, the armature will be released and the weight of the arm will carry the same into the position shown in Fig. 3.

Mounted upon a rod or shaft 25, pivoted in suitable bearings upon the base plate 8, are rocking dogs 26, 26^a, 26^b, 26^c, 26^d, 26^e, and 26^f. Each of the dogs has the rear end thereof so shaped as to engage the base plate 8 and limit the downward movement of the dog when free. Upon the end of the dog, to the right hand side, an upwardly extending lip 27 is formed, which has its front edge curved and its rear edge perpendicular to the upper surface of the dog. The under side of

the dog has a lip 28 which extends throughout its whole length and which is rounded off at the left hand edge. The levers 1^a to 1^g are each provided with a latch 29, pivoted to the lever at 30 in a slot 31, formed in the lever, the walls of which slot limit the vertical movement of the latch relatively to the switch. The first lever on the left has no latch. Below the latch and formed integrally with the lever is a lug 32 projecting toward the base plate and consisting of two parts 33 and 34. The part 33 is square in section and flat upon the end, and when the lever is in a position to close the circuit, presents a vertical surface. The upper part of the part 34 is inclined or chamfered at an acute angle.

Mounted in bearings formed in the brackets 4 and below the lower ends of the levers is a rod or shaft 35, which carries on one end a cam wheel 36 and between the brackets 4, a number of ratchet wheels 37, one wheel for each of the levers except the last. These wheels are secured upon the shaft 35 to rotate therewith and are arranged directly in line with the levers 1 to 1^g inclusive. The extension of each of the levers 1 to 1^g carries a pivoted dog 38, which is adapted to engage the teeth of the ratchet 37. The movement of the dog is such that when the lever is in its open position it engages one of the teeth of the ratchet wheel 37, and as the lever is thrown closed, moves the ratchet wheel around, thereby turning the shaft 35 and the cam wheel 36 therewith.

A switch 39 is mounted upon a vertically movable rod 40, the lower end of which rod is adapted to rest on the cam wheel 36, and the upper end of which is connected with a plunger 41, operating in a dash-pot 42. The dash-pot is suitably mounted upon a bracket 43, secured to the base 8. The switch, when in its lowermost position, is adapted to engage stationary contacts 45 and 46. The cam wheel 36 is preferably provided with seven cam faces corresponding to the first seven switch arms. One side of each cam extends substantially radially from the center of the wheel, and when the wheel is rotated by the closing of the switches, the end of the cam clears the lower end of the rod 40, and permits the rod to drop down. The dash-pot 42 is adapted to retard the downward movement of the rod. The last switch 1^g carries on its extension a spring switch member 47, which is adapted, when the arm is in its open position, to engage a stationary contact 48.

In Fig. 11, I have shown a diagrammatic view of the circuit connections of my invention. Referring now to this figure, the positive side 49 of the supply mains is connected with the terminal 10. The terminal 10^g is connected by a conductor 50, with one terminal of the armature 51 of the motor. The opposite terminal of the armature is connect-

ed by conductor 52 with the negative side 53 of the supply mains. The contact bar 9 is connected by a conductor 54 with one terminal of the magnet 21, and by the conductor 54 and a conductor 55 with one terminal of the field winding 56 of the motor, the opposite side of this field winding being connected with the conductor 52. The opposite terminal of the winding 21 is connected 10 through a high resistance 57 with the negative side 53 of the line, and by a branch conductor 58, with the contact 45. The contact 46 of the switch 39 is connected by a conductor 59, with the contact 48 of the switch 47. 15 A section of resistance 60 is connected between the contact bar 9 and the terminal 10^a. A second resistance 61 is connected between the terminal 10^a and the terminal 10^c, and is divided into sections connected with the terminals 10^b to 10^f. It will be noted that as long as the switch 39 is in its down or closed position, the winding of the magnet 21 is short-circuited as long as the last switch 1^c is open and the switch 47 closed. 20 The operation of starting the motor by the above described device is as follows: Assuming that it be desired to start the motor, the switch arm 1 is closed to first close the circuit between the carbon blocks 17 and 13 25 and 18 and 14, and finally to close together the terminals 9 and 10, by the contact device 7 thereof. The moving of the arm 1 to a closed position causes the dog 38 to move the ratchet wheel 37 thereof around, thereby 30 rotating the shaft 35 and with it, the cam wheel 36. As the cam wheel rotates, one of the cams thereof raises the rod 40 and with it the switch 39, thereby opening the short-circuit around the magnet 21. Under these 35 circumstances, current will flow from the positive side 49 to the contact 10, thence across the arm 1 to contact 9, by conductor 54, through the winding of the retaining magnet 21, and thence through the resistance 57, to the negative side 53 of the line. The magnet is thus energized and retains the arm 1 in its closed position. With the switch arm 1 closed, circuit is also established from the positive side 49 of the line to 40 the terminal 10, across the arm 1, to the contact bar 9, thence through the section 60 of resistance and through all of the resistance 61 to the contact 10^c, thence by conductor 50, through the armature 51 of the motor 45 and by conductor 52 to the negative side 53 of the line. Current is also established from conductor 54, by conductor 55, through the field 56 of the motor and thence by conductor 52 to the negative side 53 of the line. 50 The motor is thus started with all resistance in circuit. In moving the arm 1 to the closed position, the oblique wall 34 of the lug 32 of the arm engages the under face of the first rocking dog 26, and raises the same 55 into the position shown in full lines in Fig. 7.

When the arm 1 is moved to its full closed position, the cam which raises the rod 40 is moved to a position whereby the rod will move off the cam and start to descend, carrying with it the switch 39. The descent of 70 the switch 39 is retarded by the dash-pot 42, whereby the switch slowly descends. If the switch descends completely before the next succeeding switch 1^a is closed, a short-circuit for the magnet 21 will be established from 75 the positive side 49 of the line to the contact terminal 10, across the arm 1, through the rod or shaft 2, to the last arm 1^c, across the switch 47, to contact 48, thence by conductor 49, across the switch 39, and by conductor 58, through the high resistance 57, to the negative side 53 of the line. The short circuiting of the magnet 21 deenergizes the same and the first switch will fly open. It is, therefore, necessary to close the second 80 switch before the switch 39 drops to a closed position. Before the switch 39 drops to a closed position, we will assume that the second switch arm is closed. As the dog 26 is in its raised position, the latch 29 of the 85 switch arm 1^a will ride over the lip 27 of the dog 26, and engage the vertical wall thereof, and the switch arm 1^a will thus be held in a closed position. At the same time, the portion 34 of the lug 32 of the switch arm 1^a will 90 engage and lift the second rocking dog 26^a, so that when the arm 1^b is closed, the latch 29 thereof will be engaged and held by the lip 27 of the dog 26^a. The moving of the arm 1^a to a closed position causes the dog 38 95 thereof to engage the ratchet 37 to move the rod 35, and with it the cam 36, one step. The cam 36 thus being moved one step, again raises the rod 40 and with it the switch 39 to its full open position, where it will 100 again be released and drop down toward the closed position, until the third switch arm is closed to again raise it, it being understood, of course, that the third switch arm must be closed before the switch 39 bridges 105 the contacts 49 and 46. In this manner all of the switches are successively closed. When the last switch is closed, the switch 47 carried thereby will be moved off the contact 48, thereby opening the short-circuit 110 around the magnet 21 at this point, and the switch 39 may then drop down to its closed position without affecting the circuit of the magnet 21, whereby the magnet will remain 115 energized and retain the switches closed. 120 If it is desired to cut in the resistance and open the circuit through the motor, the retaining magnet 21 may be deenergized in any suitable manner and the arm 1 will be released and fly outward to the position shown 125 in Fig. 3. In moving outward the first rocking dog 26 is permitted to fall and the latch of the second arm 1^a is thus released, and the switch arm likewise flies outward. The switch arm 1^a permits the second rocking 130

- dog 26* to fall, thereby releasing the third switch arm, and in a similar manner, each switch arm releases the next succeeding arm, until all the switch arms have been released.
- 5 Any attempt to close one of the switches out of its regular order is prevented due to the fact that the flat face 33 will engage the end of the rocking dog when the dog is in its lower position, and it is only when the dog 10 has been raised to its upper position that the flat face 33 will pass beneath the end of the rocking dog. Moreover, unless the rocking dog is in the upper position, the latch 29 will not engage the lip 27 upon the dog, and the 15 rocking dog will be held in the upper position only when the preceding switch has been closed. The accidental or intentional closing of the switch arms out of their regular order is thus effectively prevented.
- 20 The motor resistance used in devices of this character is usually made of wires of sufficient capacity to carry the current for a short time, while the motor is being started, but these wires are not usually of sufficient 25 capacity to carry the current for a considerable period of time. It is, therefore, desirable to limit the time in which the switches are operated to remove the resistance from circuit. In the present instance the time is 30 limited by the switch 39. When the first switch 1 is closed, the switch 39 is moved to its full open position, but immediately starts to move closed. If the next switch is not closed before the switch 39 closes, the magnet 21 35 which retains the first switch closed, will become deenergized, and permit the first switch to open, and so on throughout the closing operation. It is thus seen that each switch must be closed within a definite period of 40 time or all of the switches that have been closed will fly open. I, therefore, am enabled to provide a time limit which limits the period in which the switches are closed to cut out the resistance.
- 45 It is obvious that the electrical connections of my invention may be varied to suit varying circumstances, that the retaining device may be varied and that the various other modifications may be made without departing 50 from the spirit of my invention as set forth in the appended claims.
- Having thus described my invention what I claim as new and desire to secure by Letters Patent is:
- 55 1. The combination with a plurality of switches adapted to be closed in a definite sequence, of mechanical means for opening the circuit through the switches when the next succeeding switch remains unclosed for 60 a time longer than a predetermined period.
2. The combination with a plurality of switches, of means set by said switches for opening the switches when part of the same remain unclosed for a longer time than a pre- 65 determined period.

3. The combination with a plurality of switches, of retaining means for holding said switches, and means set by said switches for causing said retaining means to release said switches when part of the same remain unclosed for a predetermined period. 70

4. The combination with a plurality of switches, of a retaining device for holding the same, and means operated by each switch for controlling said retaining device. 75

5. The combination with a plurality of switches, of a retaining means for holding said switches closed, mechanical means set in operation by certain of said switches for controlling said retaining means and means operated upon the closing of one of said switches for rendering said controlling means inoperative. 80

6. The combination, with a plurality of switches, a retaining mechanism for holding said switches closed, mechanical means set in operation by certain of said switches for rendering said retaining mechanism inoperative unless another of said switches is closed within a predetermined period of time and means operated upon the closing of one of said switches for rendering last mentioned means inoperative. 85

7. In a motor controller the combination with a plurality of switches, of a resistance controlled thereby, means set by the closing of the first switch and having a tendency to move to a position to cause the switches to open the motor circuit, and adapted to open the motor circuit unless all of said resistance 100 is removed from circuit within a predetermined time. 95

8. In a motor controller the combination with a resistance, of a plurality of switches for controlling the same, a switch among said switches for controlling the motor circuit, a low voltage device coöperating with said switch whereby the same is operated to open the motor circuit in event the voltage falls below a predetermined point, a switching device operatively connected with said low voltage device and adapted to cause the same to cause the circuit to be opened, means for timing the operation of said switching device, and a mechanical connection between said device and the first switch whereby said switching device is set. 110

9. In a motor controller the combination with a resistance, of a plurality of switches for controlling the same, a switch among said switches for controlling the motor circuit, a low voltage device coöperating with said switch whereby the same is operated to open the motor circuit in event the voltage falls below a predetermined point, a switching device operatively connected with said low voltage device and adapted to cause the same to cause the circuit to be opened, means for timing the operation of said switching device, a mechanical connection between said 115 device and the first switch whereby said switching device is set. 120

125

device and the first switch whereby said switching device is set, and means operated when the last switch is closed for rendering said switching device ineffective.

5 10. In a motor controller the combination with a resistance, of a plurality of switches for controlling the same, a switch among said switches for controlling the motor circuit, a low voltage device coöperating with said 10 switch whereby the same is operated to open the motor circuit in event the voltage falls below a predetermined point, a switching device operatively connected with said low voltage device to cause the same to cause the 15 circuit to be opened, means for timing the operation of said device, a mechanical connection between said switching device and each of said switches by which said device may be set.

20 11. In a motor controller the combination with a resistance, of a plurality of switches for controlling the same, a switch among said switches for controlling the motor circuit, a low voltage device coöperating with said 25 switch whereby the same is operated to open the motor circuit in event the voltage falls below a predetermined point, a switching device operatively connected with said low voltage device to cause the same to cause the 30 circuit to be opened, means for timing the operation of said device, a mechanical connection between said switching device and each of said switches by which the device may be set, and means operated upon the 35 closing of the last switch for rendering said switching device ineffective.

12. In a motor controller the combination with a resistance of a plurality of switches for controlling the same, a switch among said 40 switches for controlling the motor circuit, a low voltage device coöperating with said switch whereby the same is operated to open the motor circuit in event the voltage falls below a predetermined point, a switching device 45 operatively connected with said low voltage device and adapted to cause the same to cause the circuit to be opened, means for timing the operation of said switching device, and means operated by said switches for setting said switching device.

13. In a motor controller the combination with a resistance, of a plurality of switches for controlling the same, a switch among said switches for controlling the motor circuit, a low voltage device coöperating with said 55 switch whereby the same is operated to open the motor circuit in event the voltage falls below a predetermined point, a switching device operatively connected with said low voltage device and adapted to cause the same to cause the circuit to be opened, means for timing the operation of said switching device, means operated by said switches for setting said switching device, and means op-

erated upon the closing of the last switch for 65 rendering said switching device ineffective.

14. In a motor controller the combination with a resistance, of a plurality of switches for controlling the same, a switch among said switches for controlling the motor circuit, a low voltage device coöperating with said 70 switch whereby the same is operated to open the motor circuit in event the voltage falls below a predetermined point, a switching device operatively connected with said low voltage device and adapted to cause the same to cause the circuit to be opened, means for timing said switching device, and mechanical means for setting the same.

15. In a motor controller the combination with a resistance, of a plurality of switches for controlling the same, a switch among said switches for controlling the motor circuit, a low voltage device coöperating with said 80 switch whereby the same is operated to open the motor circuit in event the voltage falls below a predetermined point, a switching device operatively connected with said low voltage device and adapted to cause the same to cause the circuit to be opened, means for timing said switching device, mechanical 85 means for setting the same, and means operated upon the closing of the last switch for rendering said switching device inoperative.

16. In a motor controller, in combination, 90 a plurality of switches, a plurality of sections of resistance controlled thereby, means insuring the closure of said switches in a definite sequence, and mechanical means for causing said switches to open automatically if one of the same remains unclosed for a predetermined time.

17. In a motor controller, in combination, 95 a plurality of switches tending to stand in open position, a plurality of sections of resistance controlled thereby, interlocking means insuring the closure of said switches in a definite sequence and for causing each switch, when closed, to hold another switch 100 in closed position, retaining means for holding the first switch of the sequence closed, and mechanical means for rendering said retaining means ineffective if one of said switches remains unclosed for a predetermined time.

18. In a motor controller, in combination, 110 a plurality of switches tending to stand in open position, a plurality of sections of resistance controlled thereby, interlocking means insuring the closure of said switches in a definite sequence and for causing each switch, when closed, to hold another switch closed, a retaining magnet for holding the first switch of the sequence closed, and mechanical means for rendering said retaining 120 magnet ineffective if one of said switches remains unclosed for a predetermined time.

19. In a motor controller, in combination,

a plurality of switches tending to stand in open position, a plurality of sections of resistance controlled thereby, interlocking means insuring the closure of said switches 5 in a definite sequence and for causing each switch, when closed, to hold another switch closed, a retaining magnet for holding the first switch closed, a switch tending to move to a position to render said retaining magnet 10 ineffective, means for retarding the movement of said switch in one direction, and

means operated upon the closure of each of said first mentioned switches for moving said last mentioned switch to a predetermined position and then releasing the same.

In witness whereof, I have hereunto subscribed my name in the presence of two witnesses.
